PHOTOELECTRIC SPEED CONTROL

Waldemar I. Bendz, Weston, Mass., assignor to
Westinghouse Electric Corporation, East Pitts-
burgh, Pa., a corporation of Pennsylvania

Application October 7, 1947, Serial No. 778,366

4 Claims. (Cl. 250—209)

1

My invention relates to electronic speed regulating systems for correlating the travel of web or sheet material to the operation of mechanism, such as printing, or folding machinery.

It is an object of my invention to provide a photoelectric speed control of greatly increased sensitivity and reliability so as to permit, for instance, the use of control marks of less contrasting color or shade relative to the web background than practicable with known equipment of this type.

Another object of my invention, subsidiary to the one mentioned, is to provide an electronic relay circuit which secures a reliable control of machinery by two phototubes with the aid of electric circuit means of especially simple and economical design and operation.

According to one feature of the invention, I arrange two photoelectric tubes at opposite sides of a transparent or translucent web so that one tube reacts to light reflected from marks on the web while the other tube reacts to light passing through the same marks, and I connect the two tubes to an electronic relay system so that the reflectivity and transparency controlled effects acts cumulatively on the same relay equipment to jointly control the associated machinery. As a result, the speed control system is considerably more sensitive to the presence or absence of the control marks within the illuminated zone so that marks which are not discernible to the conventional systems, reacting only on reflected light or only on transmitted light, are readily scanned and responded thereto.

According to another feature of the invention, I connect the two photoelectric tubes to two respective electronic amplifiers whose output circuits are interconnected by series-connected respective resistors whose common terminal is attached to a capacitive impedance arrangement in the grid circuit of a gaseous discharge relay so that the two photoelectric tubes simultaneously produce two voltage drops across the respective resistors that act cumulatively on the relay trigger circuit.

Systems according to the invention are especially suitable for packaging or cutting machines operating with semi-transparent web material which is commonly used for many products such as candy bars or chewing gum. Hence, an embodiment of a control system according to the invention for such a machine will hereinafter be described in detail although the invention is not limited to this particular kind of machinery.

In the drawing, in which an embodiment of

2

my invention is illustrated by its electric circuit diagram and a schematic showing of the controlled regulating mechanisms, the traveling web is denoted by 1 and one of its printed marks by 2. An optical device for concentrating a beam of light on the mark comprises a lamp 3, operated from a suitable power source such as a battery 4, and a lens or system of lenses 5. The direction of web travel is denoted by an arrow D. 10 Two phototubes P1 and P2 are disposed at opposite sides of the web so that tube P1 reacts to light reflected by the mark 2, while tube P2 reacts to light transmitted through the mark 2.

Tube P1 is connected to the input circuit of 15 an amplifier tube A1, and tube P2 is similarly connected to an amplifier tube A2. The output of both amplifiers is combined to control the performance of an electronic trigger relay R which in turn controls motor-driven machinery 20 M that regulates the web travel.

More in detail, the phototube P1 with its light-sensitive cathode 7 and its anode 8 is coupled to the grid 15 of the amplifier tube A1. Tube A1 is shown as a triode, although a pentode is preferably employed to obtain a higher degree of amplification. The coupling of phototube P1 to the grid of amplifier tube A1 is through a capacitor 11 and resistors 10 and 12. This circuit is conventionally known as impulse coupling of the phototube and responds only to a rapid change 25 in the degree of illumination falling upon the cathode 7 of phototube P1. Cathode 14 of amplifier A1 is energized by a suitable source such as battery 17. The anode 16 of amplifier A1 is energized by a suitable source of potential, such as battery 19, in series with an anode load resistor 20. Potential for the grid 15 of amplifier A1 is supplied by a suitable bias from a source, such as battery 18, which is connected to the grid by 30 a grid resistor 12.

The circuit illustrated is for operation by a reference mark 2 darker than the web material 1, so that the illumination of the phototube-cathode 7 is decreased as the reference mark 2 passes under the scanning light beam. The circuit adjustments are such that bias potential 18 causes a normal flow of anode current 16 passing through the load resistor 20. The flow of anode current produces a voltage across resistor 20 negative at terminal T1, whose value depends upon the quiescent point of tube operation. With the light beam shining upon the clear web 1, cathode 7 of phototube A1 is illuminated, and phototube current, flowing through resistor 10 from the source of potential 9, causes

a voltage across resistor 10 which is positive at terminal T2. The relatively large voltage across resistor 10 and practically zero voltage across resistor 12 causes capacitor 11 to become charged with positive potential at terminal T2. As reference mark 2 passes under the scanning beam, the illumination of cathode 7 is decreased with a consequent rapid reduction of current through resistor 10. The voltage across resistor 10 drops accordingly. Capacitor 11 is then discharged through resistors 10 and 12 in series. The discharging current flowing through resistor 12 produces a voltage across resistor 12 which has a negative potential at terminal T3. This negative potential is applied to the grid 15 of amplifier tube A1 and immediately reduces the anode current of the tube A1. As a result, the voltage across load resistor 20 is rapidly reduced and terminal T1 of the tube anode circuit becomes more positive than its normal quiescent potential.

Momentarily neglecting the function of the amplifier tube A2 and its components, the positive potential of terminal T4 is also increased above its quiescent potential because of its connection to terminal T4 through resistor 21. Coupling capacitor 22 is charged through resistor 23 because of the increasing positive potential of terminal T4. Current for charging capacitor 22 flows through resistor 23, the circuit polarity being such as to make terminal T5 of resistor 23 positive relative to terminal T6.

It will be recognized that the components used with phototube P2 and amplifier tube A2 are arranged to function in a duplicate manner to that described previously in connection with phototube P1 and amplifier tube A1.

In accordance with this similarity, the elements of the circuit associated with tubes P2 and A2 are denoted by the same reference numerals as the respective elements (7 to 21) of the circuits for tubes P1 and A1 except that the prefix 1 or 10 is added to the numerals for the circuit elements (101 to 121) of tubes P2 and A2. Similarly, the terminals T11, T12 and T13 correspond to the above-mentioned terminals T1, T2 and T3, respectively.

As a reference mark 2 passes under the scanning beam, illumination of the cathode 107 of phototube P2 is decreased because of the decreased light transmission through web 1 and reference mark 2. Thus, the potential of the terminal T13 to grid 115 of amplifier tube A2 is made more negative than the quiescent potential, and the anode current of tube A2 is decreased. The voltage across load resistor 120 is decreased, and the potential of terminal T11 becomes more positive than the quiescent potential. Capacitor 22 is charged by the increasing positive potential at terminal T4 and the voltage across resistor 23 is increased by the action of reference mark 2 passing through the scanning beam together with the response of phototube P2 and its associated components.

It should be observed that the voltage across resistor 23 is made more positive at terminal T5 either by the decrease of illumination on cathode 7 of reflected-light phototube P1, or by decreasing illumination on the cathode 107 of transmitted-light phototube P2. Although the effect upon phototube P1 is amplified by tube A1, and the effect upon phototube P2 is amplified by tube A2, the output of anode circuits of these two tubes is mixed and coupled to the common capacitor 22 through the two coupling resistors 21 and 121. In this way, the simultaneous effects

of transmitted light (to phototube P2) and reflected light (to phototube P1) are mixed and summarized to greatly increase the resultant voltage change across resistor 23. Thus, the magnitude of voltage change across resistor 23 is considerably greater than in the conventional electronic regulating schemes.

As mentioned, the circuit illustrated in connection with the phototubes (such as tube P1 and the associated components consisting of resistors 10 and 12, coupling capacitor 11 and source of potential 9) is such as to respond to a mark 2 darker than the web material. As will be readily understood by anyone familiar with the art, changes in the circuit connections can be made so as to cause the electronic circuit to become responsive to the conditions existing wherein the mark 2 is lighter than the web material 1. That is, the system responds equally well to reference marks which reflect or transmit more light than the web material itself.

The foregoing description explains the relation between the change of illumination falling upon the two phototubes P1 and P2, and the changing voltage across resistor 23 which assumed a positive polarity at terminal T4. It will now be shown that the voltage across resistor 23 is used to control the packaging or cutting machinery in the required manner. The relay tube R, for instance a thyratron, has a cathode 40, a grid 41 and an anode 42. The cathode is energized by a suitable source shown as a battery 44. A source of potential, such as battery 43, commonly known as a grid bias potential, is connected between cathode 40 and grid 41 through resistor 23. A suitable direct-current anode source of potential, such as battery 46, provides voltage for anode 42 and power to operate a suitable load device such as solenoid 47.

The bias potential from source 43 is adjusted to such a value as to render tube R non-conducting as the quiescent anode current flows through amplifier tubes A1 and A2. By the previously described function, a voltage across resistor 23, positive at terminal T4, occurs as the result of register marks 2 intercepting the light beam. The occurrence of a positive potential at grid terminal T4 instantly results in conduction of the tube R and flow of anode current through solenoid 47. This current flows through the contact 48 of a timing selector switch 49 to the tube cathode 40. In this way, a current is passed through the solenoid 47 whenever a register mark passes through the scanning light beam.

Although this invention does not relate to the mechanical operation of a packaging or cutting machine itself, the appertaining control elements of a typical machine are represented by way of example for the purpose of fully explaining the operating characteristics of the control system. The drive for the machinery may consist of an electric motor 50. A pinion 51 on the motor shaft meshes with a gear 52 whose shaft 53 carries a pair of gears 54 and 55 having different numbers of teeth. Shaft 53 is axially slidable between two positions. With shaft 53 in its normal position, gear 54 mates with a gear 56 to turn the appertaining shaft 57 at what may be called a base speed. Shaft 57 is connected to feed rolls 58 and 59, which pull the web in the direction of the arrow D, normally at a base rate corresponding to the mentioned base speed of shaft 57.

When shaft 53 is shifted out of normal position, gears 54 and 56 are disengaged and gear 55 then

meshes with a gear 60 of shaft 57 to drive the feed rolls 58, 59 at a slower rate.

The flow of current through the solenoid 47 causes it to attract the forked magnet armature 61 against a biasing spring 62. Armature 61 engages a collar 63 on shaft 53 and causes lateral shifting of shaft 62 so as to disengage gears 54 and 56, and engage gears 55 and 60. In this manner, the operating speed of shaft 57 is reduced below the normal base speed as long as solenoid 47 is energized.

A cam 64 on shaft 57 controls the selector switch 49 to cyclically open and close its spring biased contact 48. Hence, the action of switch 49 is correlated with the feeding of web 1 into the mechanism of the packaging or cutting machine (not shown).

One complete cycle of operation occurs as follows. As the light of the scanning beam falls upon the clear web 1, thyratron R is non-conducting. No current flows through solenoid 47. Gears 54 and 56 are engaged and rolls 58 and 59 feed the web 1 at the base speed. As reference mark 2 intercepts the scanning light beam, thyratron R becomes instantly conducting. Current flows through solenoid 47. Shaft 53 is shifted to operate gears 55 and 60. Rolls 58 and 59 then turn at a lower speed, and the feed rate of web 1 is reduced. As the wrapping or cutting cycle of the machine progresses, cam 64 releases the spring-opened contact 48 of timing selector switch 49. This interrupts the anode current of thyratron R which immediately becomes non-conducting, and solenoid 47 is deenergized. Shaft 53 is then returned to its normal position and causes gears 54 and 56 to return rolls 58 and 59 to normal speed.

It will be understood that solenoid 47 and the gears controlled thereby, constitute a magnetically operated speed-change system, which, if desired, may be substituted by any other of the many known types of such speed changing devices without affecting the invention proper.

It will also be understood that various other modifications, well known or conventional in the electronic arts, are readily applicable such as the substitution of a rectifier and filter for direct-current power supply instead of the illustrated batteries, the substitution of transformers in place of the filament batteries shown, or the addition of further stages of amplification, as may be required.

While, in accordance with the foregoing, the substitution of any other source of energy for lamp 3, such as the provision of a transformer in place of battery 4, is possible, the use of a direct-current source such as battery 4, or the substitution of a rectified and well-filtered alternating-current power supply, offers certain advantages over the conventional alternating-current excitation of exciter lamp 3, especially when high-speed operation of web 1 is encountered. If lamp 3 is energized by alternating current, such as from the winding of a transformer, the intensity of light from lamp 3 will vary in the sinusoidal fashion of the alternating filament current of the lamp. As has been previously stated, the connections of the components with amplifier tubes A1 or A2 is such as to render the circuit responsive to a rapidly changing value of illumination falling upon the light sensitive cathodes 7 or 107. Hence, with exciter lamp 3 powered by the usual source of alternating current, the circuit is affected by the sinusoidal variation of the scanning beam intensity. The effect is detri-

mental to the maximum obtainable sensitivity because of its obvious interference with the normal function of the change in beam intensity caused by the reference marks 2. This effect is completely eliminated when lamp 3 is energized from a direct-current source. Hence, the provision of a battery 4 or of equivalent rectified and filtered power at this particular place contributes to the sensitivity of the system and, therefore, affords an improvement over the conventional electronic circuits wherein the exciter lamp is powered from an alternating-current supply.

I claim as my invention:

1. Control apparatus for web speed regulation, comprising a single source of a directed beam of light disposed on one side of the web when in operation and directed toward the web to illuminate a scanning area thereon, a photoelectric device disposed on the web side of the light source for response to light from said source reflected from the scanning area, another photoelectric device disposed on the web side opposite the light source for response to light from said source passing through the scanning area, two amplifiers connected with said respective photoelectric devices and having respective output circuits, and relay means having a control circuit, said two output circuits being connected with said control circuit and having, relative to said control circuit, the voltage polarity needed whereby a change in illumination of a given sense on either photoelectric device will produce a voltage change of a given sense in said control circuit.

2. Control apparatus for web speed regulation, comprising light source means for illuminating a web scanning area, two photoelectric devices disposed for response to light from said source reflected from and transmitted through, respectively, said area, said two devices having respective amplifying means each having an output circuit and resistance means in said output circuit, a relay means having a trigger circuit comprising a resistor and responsive to voltage impressed across said resistor, a capacitor series connected with said resistor, said two output circuits having a point of potential in common with said trigger circuit and being connected in parallel relation to each other across said series-connection of said resistor and said capacitor, whereby said voltage is cumulatively controlled by said two devices.

3. In control apparatus for an electric device utilized in connection with apparatus operating to move a web of material longitudinally of itself, in combination, two photoelectric tubes disposed relative to each other to simultaneously respond to light reflected from and transmitted through the web respectively, two electronic amplifiers having respective grid circuits connected to said photoelectric tubes and each having an output circuit, each output circuit being equipped with a resistor so as to provide a variable voltage across said resistor under control by one of said respective photoelectric tubes, a coupling circuit connected with said two resistors for cumulatively combining said two voltages, an electronic relay tube having a plate circuit and having a control electrode connected to said coupling circuit for controlling said plate circuit in response to the cumulative effect of said voltages, and an electric device connected to the plate to be controlled by said relay tube.

4. In an electric control system for an electric device utilized in connection with apparatus operating to move a web of material longitudinally

of itself, in combination, an electric device, two photoelectric tubes disposed relative to each other to simultaneously respond to light reflected from and transmitted through the web respectively, two electronic amplifiers having respective grid circuits connected to said photoelectric tubes and having each an output circuit containing a load resistor, two coupling resistors having a common terminal and having respective other terminals attached to said load resistors, respectively, a capacitor, a charging circuit for said capacitor which includes another resistor in series with said capacitor and extends through said common terminal and the load resistors of said output circuits so as to produce across said other resistor a variable control voltage determined by the joint cumulative effects of said photoelectric tubes, an electronic relay tube hav-

5

ing a trigger circuit connected across said other resistor to be subject to said control voltage, and controlling circuits for interconnecting said electric device to said relay tube.
